UNITED STATES PATENT OFFICE.

JENS A. PAASCHE, OF CHICAGO, ILLINOIS.

REGULATOR.

1,163,361.

Specification of Letters Patent.

Patented Dec. 7, 1915.

Application filed May 9, 1910. Serial No. 560,328.

To all whom it may concern:

Be it known that I, JENS A. PAASCHE, a citizen of the United States, residing at Chicago, in the county of Cook and State 5 of Illinois, have invented certain new and useful Improvements in Regulators, of which the following is a specification.

This invention relates to electric regulators which are adapted to maintain a substantially uniform fluid pressure in a tank 10 or the like by controlling the pump or other means delivering to the tank.

The invention comprises means movable by the pressure within the tank and devices 15 controlled by said means to start and stop the pump delivering to said tank, as for instance, by opening and closing a switch for an electric motor driving the pump.

The primary object of the invention is to 20 produce a regulator of the type described which is simple, durable, and efficient in operation in any position, whether vertical, horizontal or otherwise.

It is also an object to provide means in a 25 regulator for opening and closing an electric switch or the like quickly.

In the accompanying drawings, Figure 1 is a side elevation, partly in section, of a 30 regulator embodying the features of my invention. Fig. 2 is a top plan view. Fig. 3 is a fragmental detail of the connection between the operating levers. Fig. 4 is a sectional view illustrating the electric switch.

In the embodiment herein shown of my 35 invention, A is a tank adapted to contain pressure fluid, and B is a pipe leading into the tank, said pipe having a cock C therein arranged to control the flow of fluid through the pipe. The outer end of the pipe B may 40 be connected with a pump (not shown) to deliver fluid to the tank A.

A diaphragm casing 1 having a diaphragm 2 therein communicates at one side of the diaphragm with the tank A in any 45 suitable way. In the present instance said casing is supported upon the pipe B and the lower half of the casing, *i. e.* the space beneath the diaphragm, communicates with said pipe. A plunger 3 is slidably mounted 50 in the upper wall of the casing 1, said plunger having a head 4 which rests upon the diaphragm 2. Two oppositely extending

levers 5 and 6 are pivotally mounted near their ends upon a lug 7 on the upper wall of the casing 1, the inner ends 5^a 6^a of said levers, in this instance, being forked, as shown in Fig. 2, to lie at opposite sides of said lug.

In the present embodiment, the end of the fork 6^a is widened as at 8 to inclose the 60 end of the fork 5^a and said ends are pivotally connected together by means of pivot pins 9 extending through openings 10 in the fork 6^a and secured in the fork 5^a. The openings 10 are larger than the pins 9 to 65 provide a slight amount of lost motion between the two levers 5 and 6 for a purpose to appear hereinafter.

An arm 11 on the casing 1 extends outwardly beneath the lever 5 and carries at its 70 outer end a pair of long parallel electric spring contact arms 12, said arms being insulated from each other. If desired, one of the arms 12 may be longer than the other. A suitable contact device such as a sleeve 13 75 is carried at the outer end of the lever 5 and is insulated from said lever, said sleeve preferably sliding in contact with the longer one of the arms 12 and moving into and out of contact with the shorter arm, when the 80 lever 5 is swung on its pivot so as to make and break electrical connection between said arms.

14 are stops on the lever 5 and arm 11 to limit the pivotal movements of said lever. 85 Suitable binding posts 12^a may be provided for connecting wires to the contact arms 12.

Normally the lever 5 is held down, so as to keep the switch 12 13 closed, by means to be now described. A coiled spring 15 is attached at one end to a suitable stationary part, such as the pipe B, and at its other end to a threaded pin 16 which extends through an opening in the lever 6, a nut 17 being turned upon said pin above the lever 6 so that the tension of the spring 15 may be adjusted. Said spring tends to hold the lever 6 down and owing to the connection between the levers 5 and 6, the lever 5 is also held down.

The lever 6 is arranged to be engaged by the plunger 3 for moving said lever upwardly.

18 is an antifriction roller carried by the

lever 6 in position to be engaged by the plunger.

As is commonly understood, it is desirable to open and close an electric switch quickly so as to prevent arcing. To accomplish this result I have provided, in this instance, the following means. Pairs of ears 19 20 upon the levers 5 and 6, respectively, are connected together by means of links 21, said links being coiled a portion of their length to form springs 22. From an inspection of Fig. 1 it will be seen that when the lever 6 is moved upwardly by the plunger 3 to carry the resilient connecting links 21 slightly above the "dead center" for the lever 5, said connecting links 21 will quickly snap the lever 5 upwardly and open the switch 12 13, the upward movement of said lever 5 being limited by the stops 14. Similarly when the links 21 are carried below said "dead center" the lever 5 will be snapped downwardly to quickly close the switch 12 13. It is obvious that a slight movement of the plunger 3 will synchronously cause a considerably greater movement of the ears 20.

In case the pin 9 fits very loosely the lever 6 may be moved far enough to cause the spring 22 to snap lever 5 and actuate the switch before the said lever 5 is given any gradual preliminary movement, but if the pin 9 fits more closely, the lever 5 will begin to move gradually soon after lever 6 starts and they will so continue to move in unison until the dead center is reached, when the former will be snapped quickly. The adjustment or rather the relative size of pin 9 may be such that lever 5 will start at substantially the same time with lever 6, in which case a slight movement of plunger 3 will cause a relatively greater movement of both ears 19 and 20.

In the initial upward movement of the lever 6 the lever 5 will not ordinarily be affected. Continuing movement of said lever 6, however, will bring the wall of the opening 10 into engagement with the pin 9 carried by lever 5. Said lever 5 will then be moved a short distance by the lever 6, until the links 21 pass over "dead center" when the lever 5 will be snapped to its limit of movement, as above described. It will be observed that by varying the size of the opening 10 the lever 6 will be permitted to travel a greater or less extent before the walls of said opening engages the pin 9 to positively move the lever 5 as set forth above. In this way the regulator may be made to operate under any desired variation of pressure, for the reason that the sooner lever 5 starts to move and the farther it turns before the dead center is reached, the less will lever 6 have to be turned before the critical point or dead center is reached. The contact springs 12 are adjusted in length and position so that lever 5 can oscillate

through a considerable angle without opening the switch.

Adjustment at the pivot 9 determines the degree of sensitiveness or the necessary amount of change in pressure, while adjustment of spring 15 determines the absolute pressure at which the switch shall operate. Obviously there must always be a certain amount of longitudinal clearance for the pivot 9 in opening 10 due to the varying triangular relation of the pivot 9 to the stationary pivots on lug 7.

The movements of the lever 6 are steady, the upward movement of said lever being caused by the plunger 3 resisted by the spring 15, and the downward movement thereof being caused by said spring 15. The loose connection between the ends of the levers 5 6, caused by the difference in the sizes of the pivot pins 9 and the openings 10, permits the lever 5 to be suddenly moved or snapped when the line of pull of the links 21 passes "dead center" so that the switch 12 13 will be quickly opened and closed.

In operation, assuming the switch 12 13 to be closed as shown in Fig. 1, the pump is driven to force pressure fluid into the tank A until the pressure against the diaphragm 1 is sufficient to raise the lever 6 against the tension of the spring 15. When the said lever 6 is thus raised sufficiently to carry the links 21 above the pivotal center for the lever 5, said lever 5 will be snapped upwardly and the switch 12 13 opened to stop the motor driving the pump. When the pressure in the tank A falls, the diaphragm 2 and plunger 3 will sink, permitting the spring 15 to draw the lever 6 downwardly and close the switch 12 13 as above described.

I am aware that minor changes in the construction of the present embodiment may be made without departing from the invention, therefore, I do not limit myself to the exact details herein shown and described.

I claim as my invention:

1. The combination of a pressure casing having a diaphragm therein and a plunger operated by the diaphragm and working through the wall of the casing, and a switch including a pair of oppositely extending and connected levers, one of said levers resting on the plunger for operation thereby in one direction, a spring connected to said lever for operating it in the opposite direction, each of said levers having a pair of ears projecting on opposite sides thereof respectively, and springs connected to said ears for operating the other lever in either direction.

2. The combination of a casing having a pressure-operated diaphragm and plunger therein, and a lug on the casing, and a switch mechanism including a contact lever and an operating lever, said levers having forks at their ends pivoted to the opposite

sides of the lug adjacent to each other and extending in opposite directions from the lug, the forks of the levers having a lost motion connection to each other and the operating lever resting on the plunger for operation in one direction, means to operate said lever in the other direction, and a spring

connection between the levers for actuating the contact lever in either direction.

JENS A. PAASCHE.
